Assignor to
Lowell Manufacturing Co.
Letters Patent No. 1301, dated Aug. 7, 1860.

The schedule referred to in these Letters Patent and making part of the same,

To all whom it may concern,
Be it known that I, Elimir J. Key, of Lowell, in the County of Middlesex, and State of Massachusetts, have originated and designed a new pattern for Carpets, or other fabrics, of which the following is a full, clear and exact description reference being had to the accompanying drawings making part of this specification.

A. in the center is a small branch resting on the plain figure B. The corners 1, 2, 3 & 4, when matched from another branch resting on a figure similar to fig. B, C, & D, and E & F, when matched from two cross shaped blocks. Running between the center and corners is the key work 5, which connects the blocks formed by matching C. and D, and E and F.

The colors employed for the different portions of the design may be varied to suit the taste and wish of the manufacturer.
